(57) **CLAIM**

The ornamental design for a pet treat, as shown and described.

DESCRIPTION

FIG. 1 is a perspective view of a pet treat showing our new design, according to a first embodiment;

FIG. 2 is a top view of the design shown in FIG. 1, wherein the bottom view is identical thereto;

FIG. 3 is a front view of the design shown in FIG. 1, wherein the rear view is identical thereto;

FIG. 4 is a right side view of the design shown in FIG. 1, wherein the left side view is identical thereto;

FIG. 5 is a perspective view of a pet treat showing our new design, according to a second embodiment;

FIG. 6 is a top view of the design shown in FIG. 5, wherein the bottom view is identical thereto;

FIG. 7 is a front view of the design shown in FIG. 5, wherein the rear view is identical thereto;

FIG. 8 is a right side view of the design shown in FIG. 5, wherein the left side view is identical thereto;

FIG. 9 is a perspective view of a pet treat showing our new design, according to a third embodiment;

FIG. 10 is a top view of the design shown in FIG. 9, wherein the bottom view is identical thereto;

FIG. 11 is a front view of the design shown in FIG. 9, wherein the rear view is identical thereto; and,

FIG. 12 is a right side view of the design shown in FIG. 9, wherein the left side view is identical thereto.
